(57) **CLAIM**

The ornamental design for a surgical needle, as shown and described.

DESCRIPTION

FIG. 1 is a rear, left, and bottom perspective view of a surgical needle;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear, left, bottom perspective view of the surgical needle shown disposed within a holder.

The broken lines in the figures represent portions of the article or environment that form no part of the claimed design.
